The ornamental design for a media cutting device with film wrap over, as shown and described.

DESCRIPTION

FIG. 1 is a perspective view of the new design for a media cutting device with film wrap over;

FIG. 2 is a front view thereof;

FIG. 3 is a bottom view thereof;

FIG. 4 is a top view thereof;

FIG. 5 is a rear view thereof; and,

FIG. 6 is a right side view thereof, the left side view being a mirror image thereof.

The broken lines in the drawings are shown for illustrative purposes only and form no part of the claimed design. In addition, the surface shading illustrated in the drawings is provided merely to highlight the contour of design; it is not intended to be illustrative of texture or gloss.
